(57) **CLAIM**

The ornamental design for a pair of earphones, as shown and described.

DESCRIPTION

FIG. 1 is a perspective view of an earphone of a pair of earphones showing our new design, the earphone is shown separately for ease of illustration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of an earphone of a pair of earphones, shown separately for ease of illustration;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of a third embodiment of a pair of earphones thereof;

FIG. 16 is a second perspective view of an earphone;

FIG. 17 is a front view thereof;

FIG. 18 is a rear view thereof;

FIG. 19 is a left side of an earphone of a pair of earphones shown separately for ease of illustration thereof;

FIG. 20 is a right side of an earphone of the pair of earphones shown separately for ease of illustration thereof;

FIG. 21 is a top view thereof; and,

FIG. 22 is a bottom view thereof.

The design which is claimed is shown in solid lines in the drawings. The broken lines depict environment that forms no part of the claimed design.

1 Claim, 22 Drawing Sheets
